UNITED STATES PATENT OFFICE.

HENRY E. WARREN, OF NEWTON, MASSACHUSETTS.

MECHANISM FOR OPERATING VALVES OR OTHER CONTROLLERS.

SPECIFICATION forming part of Letters Patent No. 787,136, dated April 11, 1905.

Application filed May 28, 1904. Serial No. 210,216.

To all whom it may concern:

Be it known that I, HENRY E. WARREN, a citizen of the United States of America, and a resident of Newton, in the county of Middlesex and Commonwealth of Massachusetts, have invented certain Improvements in Mechanism for Operating Valves or other Controllers, of which the following is a specification.

The invention relates to mechanism for operating valves or other controllers for hydraulic apparatus, clutch mechanism for machinery, rheostats for electrical motors, or any apparatus in which motion in one or alternating directions is to be effected or indicated. It is an improvement upon the mechanism shown and described in Letters Patent No. 752,491, granted to me February 16, 1904; and it consists in a fluid system which is in operative connection with a cylinder and piston therein, which may be referred to herein as an "actuator," and with mechanism to cause a movement of the fluid and change the pressure in the system, which mechanism may be designated "primary means," and a valve connected with the actuator and operated simultaneously therewith, which valve may be designated "secondary means," to act upon the fluid in the system and tend to neutralize the effect produced through the primary means and when the primary means have ceased action to restore the actuator to its normal position.

In the drawings, Figure 1 is a sectional elevation of the valves and fluid system and the actuator arranged to operate a rheostat for an electric motor. Fig. 2 is a sectional elevation of the improvements applied to a controller consisting of a valve similar to a globe or gate valve using a single-port valve as the primary.

Corresponding parts are indicated by the same letters throughout the drawings, wherein, referring to Fig. 1, the actuator B operates a double-contact rheostat R R', which regulates the current for an electric motor M. The rheostat contact-arm r^2 , which is shown in its middle or neutral position, is operated by a pinion p through its engagement with rack-teeth t on the rod A, which is attached

to and extends out from the piston or actuator B, adapted to be reciprocated within the cylinder C. The secondary means consists of a stem s , which extends from the end of the piston B opposite to the arm A through the other end of the cylinder C and into a valve-chamber c' . Within the chamber c' the stem s is reduced, as at r , to form a valve. The chamber c' is also provided at its respective ends with an exhaust-port b' and an inlet-port b^2 for fluid under pressure. Midway between these two ports the chamber c' has an annular recess d , with which is connected a fluid-supply pipe G, in which a throttle-valve, as g' , may be placed. Fluid under pressure is supplied to the system through the primary means, consisting of a valve E, provided with an inlet-port e' and exhaust-port e^2 . The actuator-cylinder C also has two inlets for fluid under pressure, one, g^2 , from the pipe G upon one side of the piston B and another, g^3 , upon the other side of the piston B. By reason of the enlarged projection A^2 at one side of the piston B it will be observed that a much smaller surface is exposed to the pressure of fluid upon that side of the piston than upon the opposite side or that from which the stem s projects.

In the construction shown in Fig. 1 the valve E may be operated by hand or by connection with a motor. The operation is as follows: Suppose the valve E is raised so as to open the supply-port e' . Fluid will immediately flow through into the pipe G and through the inlet g^2 into the cylinder C at the left of the piston B and overcome the pressure of fluid upon the opposite side of the piston B supplied through the inlet g^3 and cause the piston B to move to the right, and with it the rod A, which, by means of the rack t thereon in engagement with the pinion p , will turn the pinion and its shaft w to the right and also the upper end of the contact-arm r^2 , which is secured to the same shaft. Thus the upper end r^2 of the contact-arm will make contact with the portion R of the rheostat and the lower end r^3 with the circuit-closing contacts $77'$. The metal lower end r^3 of the contact-arm is insulated from the upper end r^2 and from the shaft w by non-conducting material.

n, and as soon as the ends of the contact-bar are respectively in contact with the rheostat *R* and the contacts *l l'* current will flow from the main conductor *x*, through the contact *l'*, 5 the resistance *R*, arm *r²*, shaft *w*, conductor *m'*, to the motor *M*, out at the conductor *m²*, through contact *l*, arm *r³*, contact *l'*, and conductor *x'*, and by as much as the arm *r²* is moved to the right over the rheostat *R* by so 10 much the resistance will be decreased and the current flowing to the motor increased. As soon as the piston *B* has moved to the right sufficiently far to open the valve *v*, so as to discharge fluid through the port *b'* as fast as 15 it enters the system through the valve *E*, further movement of the piston *B* to the right will cease, and as soon as the valve *E* is closed the continued escape of fluid through the port *b'* will permit the pressure of fluid through 20 the inlet *g³* to move the actuator-piston *B* back or to the left until the valve *v* is closed, and the parts will then come to rest in the position shown in Fig. 1 and the motor *M* will stop. It will be understood that if the 25 valve *E* is moved downward, so as to open the port *e²*, fluid will escape from the pipe *G* and from the cylinder *C* through the port *g²*, and thus cause the piston *B*, with the rod *A*, to move to the left, thereby turning the ends *r²* 30 of the contact-arm respectively into contact with the rheostat *R'* and the contacts *l l'* and closing the circuit from the main conductor *x*, through *l'*, *r³*, *l*, conductor *m²*, to the motor *M*, by which it will be turned in the opposite 35 direction. Thence the current will flow out through the conductor *m'*, shaft *w*, arm *r²*, resistance *R'*, contact *l'*, and conductor *x'*. As soon as the piston *B* has moved sufficiently 40 far to the left to cause the valve *v* to open the inlet-port *b²*, so that fluid will flow into the system as fast as it flows out by the port *e²*, the piston *B* will come to rest, and when the valve *E* is closed fluid flowing in at the port *b²* will move the piston *B* to the right until 45 the port *b²* is closed, and the parts of the mechanism will again come to rest in the middle position, as illustrated, the electric circuit will be opened, and the motor will stop.

In Fig. 2 a modified construction is shown 50 wherein the valve *A'* is operated by the actuator-piston *B* in a cylinder *C*. In this instance the primary means consists of a valve *E³*, which serves only as an outlet for fluid from the cylinder *C* through the pipe *G*, while the secondary means or valve *v'* serves as an inlet 55 for fluid under pressure upon one side of the piston *B* and the port *g³* for atmospheric pressure upon the opposite side thereof. In this arrangement the valve *A'* regulates the flow 60 of fluid to a prime motor supplied through the port *H* and discharged at the port *I*. In

Fig. 2 the valve *E³* is shown as operated by an indicating hand-wheel *k* and, as heretofore stated, serves only as an exhaust-port for the cylinder *C*. When this valve *E³* is opened, fluid will escape from the cylinder *C* above the piston *B*. Immediately the pressure of fluid upon the under side of the valve *A'* will raise it and the piston *B* and open the valve *A'*, also it will open the valve *v'* and admit fluid under pressure through the port *b²*, which will directly compensate for the fluid flowing out through the pipe *G* and bring the piston *B* to a state of rest. Any variation in the position of the valve *E³* will cause a corresponding variation in the position of the valve *v'*, and when the valve *E³* is closed the pressure above the actuator-piston *B* will immediately become sufficiently great to force it downward and close the valve *A'*.

The primary valve *E*, as shown in Fig. 1, may be connected by a pipe *G* with both the port *g²* and port *g³* of the cylinder *C*, so that the piston *B* may be operated in both directions through the action of valve *E* in a manner similar to that shown in Fig. 5 of my said Patent No. 752,491, excepting, of course, the so-called "compensating-cylinder" will be omitted.

I claim—

1. In combination, mechanism for operating controllers for hydraulic, electric or other apparatus, consisting of an actuator, a fluid system in operative connection with the actuator, primary means to effect movements of the fluid in the system to operate the actuator and secondary means operated with the actuator, each operation of which secondary means effects a movement of fluid in the system which tends to neutralize the effect of a movement produced through the primary means and thereby stop the actuator, and also causes the actuator to be restored to normal position when the movement effected through the primary means ceases.

2. In combination, a valve, an actuator for the valve, a fluid system in operative connection with the actuator, primary means to effect a change in the fluid-pressure in the system and thereby move the actuator, and a secondary valve connected with and operated by the movement of the actuator, each operation of which secondary valve effects a change of fluid-pressure in the system that tends to counteract the change produced through the primary means, and causes the actuator to be restored to normal position when the effect through the primary means ceases.

HENRY E. WARREN.
